UNITED STATES PATENT OFFICE.

HENRY C. HARRISON, OF PORT WASHINGTON, NEW YORK, ASSIGNOR TO WESTERN ELECTRIC COMPANY, INCORPORATED, OF NEW YORK, N. Y., A CORPORATION OF NEW YORK.

ACOUSTIC DEVICE.

Application filed July 17, 1923. Serial No. 652,013.

To all whom it may concern:

Be it known that I, HENRY C. HARRISON, a citizen of the United States, residing at Port Washington, in the county of Nassau, 5 State of New York, have invented certain new and useful Improvements in Acoustic Devices, of which the following is a full, clear, concise, and exact description.

This invention relates to acoustic devices, 10 the object being to provide an acoustic device capable of faithfully and efficiently reproducing all vibrations in the sound range and particularly the vibrations of the lower frequencies.

15 In general, the invention provides an electro-magnetic device having a vibrating system, with restoring means capable of exerting a force which varies with the displacement of the vibrating member in substantially 20 the same manner as the magnetic pull of the steady field on the vibrating member varies.

25 In one embodiment the invention contemplates a loud speaking receiver of the balanced armature type, in which the armature is balanced against the steady pull of the magnet by means of a pair of resilient strips clamped at both ends and attached at opposite ends of the armature for substantially 30 balancing the armature in any position in the magnetic field.

Referring to the drawings:

35 Fig. 1 is a view, part in section, of an electromagnetic system for loud speaking receivers embodying the invention;

Fig. 2 is a cross-sectional view through the armature supporting means;

Fig. 3 is a sectional view taken on line 3—3 of Fig. 1;

40 Fig. 4 shows comparative curves of operation of present receivers and those embodying the invention;

Fig. 5 shows a loud speaking receiver embodying the invention in a modified form;

45 and

Fig. 6 is a view through section 6—6 of Fig. 5.

In reproducing speech or music, frequen-

cies below the resonant frequency of a receiver, or of a similar electromagnetic reproducing device, are usually poorly reproduced because of the high elastic reactance of the device in this region. This elastic reactance is partly supplied by the steady magnetic field and partly by a restoring elasticity and unless these have nearly identical force versus displacement characteristics the elastic reactance cannot be made small and the natural frequency cannot be brought down to a low audible frequency.

Referring to the curves shown in Fig. 4, A represents a typical force versus displacement curve for the steady field of a receiver and B the force versus displacement curve of a restoring elasticity, such as a reed or a spring supported armature. From the curves A and B it is evident that the force shown by curve B at zero separation must be greater than that shown by curve A to prevent freezing of the armature to the pole pieces. The net elasticity operative on the armature, and which determines its natural frequency is the difference between the elasticities shown by curves A and B and is represented by the slope of curve F. A vibrating system having an elasticity curve of this character produces distortion in reproductions due to the addition of harmonics. To avoid these distortions it is necessary either to make the net elasticity very small 50 and substantially constant, either by a magnetic field giving the characteristic, as shown by curve D, or to apply a restoring force having characteristics shown by curve C, which is a curve of the same order as curve A. Curve C is shown plotted on the opposite side of the horizontal axis for the reason that this force opposes that one to the steady magnetic field. For small separations between the armature and the pole 55 pieces of the receiver, the pull on the armature due to the magnetic field varies approximately inversely as the square of the separation. Both curves, A and C, are therefore approximately parabolas. The first solution shown by curves B and D in-

volve in general a loss in efficiency as it would require a substantially large separation between the pole pieces to change the magnetic field to have the same characteristics as shown by curve D. Therefore, for the purpose of describing the invention, the structures which have the characteristics shown by curves A and C will be described.

In the embodiment shown in Figs. 1, 2 10 and 3, a core 11, having two arms 12 and 13, carries a coil 14, which when connected to a source of electrical energy furnishes a steady magnetic field. If preferred, the coil 14 and the core 11 may be replaced by a 15 suitable permanent magnet. The core 11 may be supported on a case 15, (only part of which is shown and which may be of any suitable form) by the studs 16 and the screws 17. Secured to the ends of the arms 12 and 13 of the core 11 are bifurcated pole pieces 18 and 19, preferably of soft iron laminations. Within the pole pieces 18 and 19 coils 20 and 21 are supported in any 20 suitable manner. An E-shaped support 22 25 of non-magnetic material, carrying an armature 23, which extends through the openings in the coils 20 and 21 and between the opposing extremities of the poles 18 and 19 may be supported by screws 35 or other 30 suitable means in the case 15. The arms 24 and 25 of the support 22 are provided with recesses 26 and 27, respectively, and the middle arm 28 with a recess 29. The armature 23 extends through the recesses in these arms 35 and is supported on the arms 24 and 25 by means of resilient members or springs 30 and 31, respectively. These springs are short and so designed as to offer a resistance to the movement of the armature 23, which 40 varies in substantially the same manner as the magnetic pull on the armature. In this case this resistance varies as shown by curve C in Fig. 4. For magnetic systems having a maximum movement of .014 inches, springs 45 having a thickness of .002 inches and an unsupported length of about .060 inches have been found satisfactory. The armature 23 may be supported intermediate its extremities by any suitable means, such as a pin 50 34, one end of which fits loosely in the armature 23 so there will be no initial stress on the springs 30 and 31 and the other end may fit snugly in the arm 28. This pin has preferably a reduced middle section so as to add 55 no stiffness to the vibrating system. Its function is to provide a definite center of oscillation for the armature and may be omitted if the springs 30 and 31 are exactly the same and disposed exactly symmetrical 60 with respect to the poles. Operatively associated with the armature 23 by means of rod 32 is a diaphragm 33 of the usual type, which operates into a horn or distributes the sound in any well known manner. The 65 rod 32 is preferably adjusted so there will

be no stress exerted on the armature by the diaphragm at maximum separation.

It will be noted from the curves shown in Fig. 4 that if the pull due to the springs 30 and 31 varies at exactly the same rate 70 and by the same amount as the pull due to the magnetic field, the armature would have zero elasticity and zero natural period for all displacements and would therefore remain in any position in the magnetic field 75 to which it would be moved. As the armature would freeze under this condition for zero separation, it is preferable to provide a restoring force greater than the magnetic pull by an amount proportional to the displacement. One having a low constant elasticity of such a value as to give the vibrating system a low natural frequency of about 50 to 200 cycles per second has been found very satisfactory. This will not only prevent freezing at zero separation but will 80 make the device slightly more efficient at the lower frequency range where it is desirable. For very slight deflections of the springs 30 and 31 the restoring force is quite 85 small, but as the deflection is increased the force increases rapidly and at substantially the same rate as the pull due to the steady field.

The modification shown in Figs. 5 and 6 90 differ from the one hereinbefore described only in the manner of supporting the armature. A support 40, which corresponds to the support 22 in the previous modification, has a convex bearing surface 41 on its middle arm, against which the armature 42 is held by a resilient member 43 having a knife-edge 44 engaging a groove 45 in the armature 42, the bearing surface 41 should have a large radius. For the structure shown a 100 2" radius has been found to be satisfactory. As the armature 42 vibrates, the distance between the bearing point on the member 43 and the pivoting point on the surface 41 105 varies.

The restoring force varies with this change in distance and is substantially proportional thereto. The restoring force also changes with the pressure exerted on the armature by the member 43 which is flexible 110 for vibrations of small amplitudes and acts as a variable load. As the change in the distance between the supports and the change in the load are both in the same direction the force displacement curve may 115 be made to increase at such a rate as to substantially equal that due to the steady magnetic field or any desired part of it at all armature positions.

Although the invention has been described 120 in connection with a telephone receiver, it may obviously be applied to electromagnetic transmitters, recorders, reproducers or any electromagnetic apparatus employing 125 vibrating systems.

The invention claimed is:

1. In a sound reproducing system, a diaphragm, a magnet, an armature for said magnet operatively connected to the diaphragm, and means for substantially balancing the magnetic pull on the armature in all positions.
2. In a sound reproducing device, a diaphragm, a magnet, an armature for said magnet operatively connected to said diaphragm, and means compensating to a substantial extent for the steady magnetic pull at all armature positions.
3. In an acoustic device, a magnet having a substantially constant magnetic field, a vibrating member disposed in the field of said magnet, and means for balancing the pull of the magnetic field on said member, said means having a stiffness such that its restoring force is slightly greater than the magnetic pull for substantially all positions of the vibrating member by an amount proportional to the displacement of the vibrating member from its neutral position.
4. In an acoustic device, a magnet having a substantially constant field, an armature disposed in said field, and resilient supports for said armature, said supports producing a restoring force which varies with the minute displacement of said armature in substantially the same manner as the magnetic pull on said armature but in the opposite direction.
5. In a magnetic system, a magnet, a vibrating member operatively associated with said magnet, and means for offering a mechanical impedance to the armature which varies in the same manner as the mechanical impedance due to the force of the steady magnetic pull exerted thereon.
6. In an acoustic device, a diaphragm having a substantially steady magnetic field, an armature connected to said diaphragm and mechanically associated with said magnet, and means for balancing the armature against the pull of said magnet, said means being of such stiffness as to cause a resisting force which varies with the displacement of said armature in substantially the same manner as the pull of the magnetic field.
7. In a sound reproducing mechanism, a diaphragm, a magnet having a steady magnetic field, an armature for said magnet responsive to current variations operatively connected with the diaphragm, and means offering an impedance to the movement of the armature substantially opposite in phase and equal in magnitude to the mechanical impedance due to the steady magnetic field.
8. In a sound reproducing mechanism, an electromagnet producing a steady magnetic field, an armature, a diaphragm operatively connected with said armature, and means for producing a force in the armature resist-
- ing the magnetic force of the steady field 65 and larger by an amount proportional to the displacement of the armature for substantially all positions.
9. In a sound reproducing device, a diaphragm, an electromagnet responsive to the current variations, an armature for the electromagnet pivotally supported between its ends and operatively connected at one end to the diaphragm, and damping means connected with the other end of said armature 75 adapted to resist the movement of the armature in response to the magnetic force thereon and in direct proportion to the magnetic force.
10. In a sound reproducing device, a diaphragm, an electromagnet responsive to current variations, an armature for the electromagnet pivotally supported between its ends and operatively connected at one end to the diaphragm, and a spring connected to the other end of said armature and so proportioned when mounted that its resistive force to the movement of the armature in response to the magnetic force is in direct proportion to such force. 80
11. The method of controlling a vibrating system which consists in applying a steady magnetic field and an opposing resisting force to a vibrating member, the resisting force varying with the displacement of the member in a manner such that the difference between the resisting force and the magnetic pull gives a constant elasticity. 85
12. The method of controlling a vibrating member which consists in applying thereto a steady magnetic field and an opposing resisting force which varies with the displacement of the vibrating member in the same manner as the pull due to the magnetic field varies. 100
13. The method of controlling the vibrating system of a magnetic device which consists in substantially counter-balancing the elasticity in the magnetic field by a second elasticity varying with the displacement of the armature in the same manner as the elasticity of the magnetic field. 110
14. The method of controlling the vibrating system of a magnetic device which consists in applying thereto a restoring force which varies with the displacement of the vibrating system in substantially the same manner as the force due to the steady magnetic flux varies with the displacement of the vibrating system. 115
15. The method of controlling a vibrating member in a magnetic system which consists in applying a resisting force to the vibrating member which varies substantially inversely as the square of the displacement of the vibrating member. 120
16. In a vibratory electromagnetic system responsive to frequencies within the voice 125

range, a magnet, a vibrating armature for said magnet, and resilient means for placing the natural frequency of vibration of the armature in the lower range of voice frequencies.

17. In a vibratory electromagnetic system responsive to frequencies within the voice

range; a magnet, a vibrating armature for said magnet, and resilient means for making the armature highly responsive to the lower range of voice frequencies.

In witness whereof, I hereunto subscribe my name this 11 day of July A. D., 1923.

HENRY C. HARRISON.
